UNITED STATES PATENT OFFICE.

CHARLES L. WECHT, OF LOGANSPORT, INDIANA.

BEDCLOTHES-HOLDER.

1,251,308.

Specification of Letters Patent. Patented Dec. 25, 1917.

Application filed February 15, 1915. Serial No. 8,373.

To all whom it may concern:

Be it known that I, CHARLES L. WECHT, citizen of the United States, residing at Logansport, in the county of Cass and State 5 of Indiana, have invented certain new and useful Improvements in Bedclothes-Holders, of which the following is a specification.

My invention relates to improvements in apparatus for holding the bed clothes in 10 proper position upon the mattress.

It consists in the simple and efficient mattress-straddling and bed-clothes-holding clamp, hereinafter described and definitely claimed.

15 In the accompanying drawings forming a part of this specification and in which like numerals are employed to designate like parts throughout the same,

Figure 1 is a plan view of a bed, showing 20 my improved clamps applied thereto,

Fig. 2 is a side elevation of the clamp in use,

Fig. 3 is a side elevation of the clamp removed, and,

25 Fig. 4 is a side elevation of one of the friction pads.

In the drawings, wherein for the purpose of illustration is shown a preferred embodiment of my invention, the numeral 5 designates a bed of any well known or preferred 30 type, having thereon a mattress 6, upon which is arranged the bed clothes 7.

The numeral 8 designates a longitudinally curved leaf spring, which is suitably resili- 35 ent and constitutes the body portion of the clamp. Rigidly secured to the opposite ends of the leaf spring 8, by bolts or the like, are transverse heads 9, upon which are secured highly elastic friction pads 10. These friction pads are arranged upon the inner faces 40 of the heads 9 and are preferably secured thereto by bolts or rivets 11, the inner ends of which are preferably counter sunk. The highly elastic friction pads 10 are prefer- 45 ably formed of highly elastic rubber, such as sponge rubber, while the same may be formed of ordinary rubber or felt or the like.

In the use of the clamps, four of them 50 may be advantageously arranged upon the bed 5, as illustrated in Fig. 1, while this number may be varied as found advanta-

geous. Each clamp is passed about the edge of the mattress, as illustrated in Fig. 2, with the upper friction pad 10 engaging the upper surface of the bed clothes and the lower 55 friction pad engaging beneath the mattress, either with the bed clothes folded thereabout, as shown in Fig. 2, or directly with the lower side of the mattress. It is obvious that the invention is not restricted to the 60 precise manner in which the clamp is applied to the bed clothes and mattress.

It is of the essence of my invention that the opposed ends of the body spring 8 be capable of separation to an extent sufficient 65 to adapt the spring to straddle a mattress and bed clothes thereon; and it is equally essential that the pad-heads and the elastic pads be extended laterally a considerable distance at opposite sides of the vertical plane of the 70 body spring. This latter will be appreciated as an important advantage when it is stated that without the body spring being unduly large, the pads, relatively arranged as defined, serve, when the clamp is opened to the 75 extent shown in Fig. 2, to afford large frictional surfaces adapted to accommodate themselves to inequalities of and take secure hold of the mattress and bed-clothes in the vertical plane of the body spring as well as 80 at opposite sides of said plane, and in that way preclude casual displacement of the clamp even when a restive child is under the clothes. I would also have it understood that the capacity of the clamp to resist 85 casual displacement is due in a measure to the fact that the pads and pad-heads are directly backed by the ends of the circular spring body which enables said body when expanded, as shown in Fig. 2, to strongly 90 hold the pads to their work.

Having thus described the invention, I claim:—

As a new article of manufacture, the herein described mattress-straddling and bed-clothes-holding clamp, consisting essentially of a circular spring body having end portions that normally rest at obtuse angles to the remainder of the body and converge in a direction away from the center of the body, 95 rigid pad-heads directly backed by and fixedly connected to and arranged parallel with 100

said end portions, and elastic pads carried at the inner sides of and arranged parallel to the pad-heads; said pad-heads and pads corresponding in area and extending laterally 5 at right angles in opposite directions from the plane of the spring body when the clamp is in operative position, as specified.

In testimony whereof I affix my signature in presence of two witnesses.

CHARLES L. WECHT.
